Inventor

John Edward Ogden

By his Attorney

E. W. Marshall

UNITED STATES PATENT OFFICE.

JOHN EDWARD OGDEN, OF MOUNTAINVILLE, NEW YORK.

ANCHORAGE.

Application filed June 11, 1921. Serial No. 476,646.

This invention relates to an improved anchorage for securing a threaded element such as a bolt or similar fastening device in an aperture in a wall or other building structure of stone, brick, cementitious or like material. The invention further relates to methods of forming such an anchorage.

One of the objects of my invention is to provide an anchorage having relatively hard and relatively soft metal pieces so combined as to form a firm and secure anchorage.

Another object of the invention is to provide a new method for forming an anchorage comprising relatively hard non-elastic metal and relatively soft ductile metal.

Further objects of the invention will appear as the description proceeds.

Referring to the drawings, Fig. 1 is a transverse section of a portion of a wall showing an aperture or hole therein and illustrating one method of forming my improved anchorage.

Fig. 2 is a transverse sectional view of the construction shown in Fig. 1.

Fig. 3 illustrates the anchorage shown in Fig. 1 after the soft metal sleeve has been tamped or compressed.

Fig. 4 is a transverse sectional view of the structure shown in Fig. 3 taken substantially on line 4—4 of Fig. 3.

Fig. 5 is a sectional elevation similar to Fig. 1 but showing another form of the invention.

Fig. 6 is a transverse sectional view of the structure shown in Fig. 5.

Fig. 7 is a sectional elevation illustrating another embodiment of the invention.

Fig. 8 is an end view of the mandrel used in the form of the invention shown in Fig. 7.

Fig. 9 is a sectional elevation of the anchorage shown in Fig. 7 but illustrating the anchorage after the soft metal sleeve has been compressed.

Fig. 10 is a transverse sectional view taken substantially on line 10—10 of Fig. 9.

Figs. 11 and 12 illustrate, in sectional elevation and transverse section, still another form of the invention.

Figs. 13 and 14 show in sectional elevation and transverse section another form of the invention and

Fig. 15 is a sectional elevation of still another form of the invention.

Like characters of reference designate corresponding parts in all the figures of the drawing.

Referring first to the form of the invention illustrated in Figs. 1 to 3 inclusive, I have shown a portion of a wall 20 of a building structure, this wall having an aperture or hole 21 bored therein to receive a bolt 22 or other fastening device. Assuming that the wall 20 is formed of stone, brick or cementitious material it will be evident that some form of anchorage must be provided between the bolt 22 and the surface of the hole 21.

The form of anchorage shown in Figs. 1—4 comprises a tubular member shown in the form of a spiral 23, the diameter of this member being substantially that of the hole 21. This tubular spiral member is formed of non-elastic, relatively hard, expansible, material, and there is positioned within this tubular member another tubular member or sleeve 24 of relatively soft ductile material. The bolt or retaining member 22 is positioned within the sleeve 24 and in order to form an anchorage the soft metal sleeve 24 is compressed within the opening 21 in any suitable manner as by tamping.

In Fig. 3 I have shown an anchorage after the sleeve 24 has been compressed and it will be noted that the compression of the sleeve forces the soft ductile metal into engagement with the threads of the bolt 22 and also forces the spiral 23 outwardly into firm engagement with the wall of the opening 21. It will also be noted that the soft metal of the sleeve 24 is forced through the opening in the spiral and also engages the wall of the opening 21. There is thus formed a firm and secure anchorage, the engagement of the spiral 23 with the wall of the opening effectively preventing the withdrawal of the anchorage and this spiral of hard metal also strengthening the anchorage structure.

In Figs. 5 and 6 I have illustrated another form of the invention in which the spiral tubular member 23 is positioned between the bolt 22 of the soft metal sleeve 24. It will be evident that compression of the sleeve 24 shown in Fig. 5 will force this sleeve into firm engagement with the surface or wall of the opening 21 and furthermore the ductile material will be forced into engagement with the spiral 23 and with the threads on the bolt 22.

In Figs. 7, 8, 9 and 10 I have illustrated another method of forming the anchorage and in this embodiment as in the form of

the invention shown in Figs. 1-4, the spiral 23 is positioned between the soft metal sleeve 24 and the surface or wall of the opening 21. Instead, however, of positioning the 5 bolt 22 within the sleeve 24 before compressing the sleeve, in this form of the invention I use a mandrel 25, the sleeve 24 being compressed by means of a tubular member or sleeve 26 which is positioned on 10 and is adapted to slide on the mandrel thereby compressing or swaging the soft metal sleeve 24 into engagement with the mandrel 25 and also forcing the metal of the sleeve 24 outwardly through the openings in the 15 spiral 23 and pressing the spiral into firm engagement with the wall of the opening 21.

In Figs. 9 and 10 the anchorage formed by this method is shown and from these figures it will be seen that after the mandrel 20 has been withdrawn the inner surface of the sleeve 24 is formed with a plurality of inwardly extending longitudinal ribs 27 into which threads may be cut by the threads on the bolt 22.

25 In Figs. 11 and 12 still another form of the invention is shown and in this form the spiral 23 of relatively hard metal is positioned in the body of the sleeve 24 of relatively soft metal. In order to form the anchorage, the sleeve 24 with the spiral 23 formed therein is positioned within the opening in the wall and the sleeve is compressed by one of the methods above described. The compression of the sleeve 30 shown in Figs. 11 and 12 will force the sleeve into engagement with the wall of the opening 21 and also with the bolt 22, if the method shown in Figs. 1-4 is used, or with the mandrel 25, if the method shown in 35 Figs. 7 to 10 is used. Such a compression of the sleeve would also obviously more or less distort and compress the spiral 23.

In Figs. 13 and 14 still another embodiment of the invention is illustrated. In this 40 form a plurality of longitudinally extending hard metal strips 28 is positioned within the opening 21 in the wall, these strips as shown in Fig. 13 being shorter than the depth of the opening in the wall. The sleeve 45 24 of relatively soft material is positioned within the opening in the wall and also within the strips 28. When the sleeve 24 is compressed by one of the methods already described the relatively soft ductile material 50 will be forced outwardly between the strips 28 into engagement with the wall of the opening 21 and this material will also force the strips 21 into firm engagement with the inner surface of the opening. The strips 55 60 therefore assist in strengthening the anchorage and in holding it in firm engagement within the opening 21.

Fig. 15 shows still another form of the invention in which the tubular member is 65 formed of coarse netting or wire mesh 30.

The soft metal lining 24 is pressed through the mesh and engages the bore of the opening and also presses the wire into engagement with the wall of the bore.

From the above description it will be seen 70 that a firm and secure anchorage may be formed of relatively hard and relatively soft metal pieces, these pieces being tamped or pressed into engagement with each other and with the wall or supporting structure. 75

Although certain specific embodiments of the invention have been illustrated and described it will be evident that the invention is capable of further modifications and that further changes in the construction and in the arrangement of the co-operating parts may be made without departing from the spirit or scope of the invention as set forth in the following claims.

What I claim is:

1. The method of anchoring a threaded element which consists of forming a recess in the body to which the element is to be anchored, inserting in said recess a deformable sleeve of relatively soft, ductile material with a spiral tubular member of relatively hard material adjacent the sleeve, inserting a threaded element within the sleeve, holding the inner end of the sleeve against inward longitudinal movement and applying inward longitudinal pressure to the outer end of the sleeve whereby the sleeve and tubular member are brought into tight engagement with the surface of the wall of the bore. 90

2. The method of anchoring a threaded element which consists of forming a recess in the body to which the element is to be anchored, inserting in said recess a deformable sleeve of relatively soft, ductile material, a spiral tubular member of relatively hard material outside the sleeve, inserting a threaded element within the sleeve, holding the inner end of the sleeve against inward longitudinal movement and applying inward longitudinal pressure to the outer end of the sleeve whereby the sleeve and tubular member are brought into tight engagement with the surface of the wall of the bore. 100

3. The method of anchoring a threaded element which consists of forming a recess in the body to which the element is to be anchored, inserting in said recess a deformable sleeve of relatively soft, ductile material with a tubular member having a spiral opening therein adjacent the sleeve, inserting a threaded element within the sleeve, holding the inner end of the sleeve against inward longitudinal movement, and applying inward longitudinal pressure to the outer end of the sleeve whereby the sleeve and tubular member are brought into tight engagement with the surface of the wall of the bore. 110

4. The method of anchoring a threaded 130

- element which consists of forming a recess in the body to which the element is to be anchored, inserting in said recess a deformable sleeve of relatively soft, ductile material 5 with a spiral tubular member of relatively hard non-elastic material adjacent the sleeve, inserting a threaded element within the sleeve, holding the inner end of the sleeve against inward longitudinal movement and 10 applying inward longitudinal pressure to the outer end of the sleeve whereby the sleeve and tubular member are brought into tight engagement with the surface of the wall of the bore.
- 15 5. The method of anchoring a threaded element which consists of forming a recess in the body to which the element is to be anchored inserting in said recess a spiral tubular member of non-elastic material with a 20 sleeve of relatively soft, ductile material within said tubular member, inserting a threaded element within the sleeve, holding the inner end of the sleeve against inward longitudinal movement and exerting inward 25 longitudinal pressure against the outer end of the sleeve thereby forcing the ductile material through the openings in the tubular member into tight engagement with the wall of the recess.
- 30 6. The method of forming an anchorage which consists of forming a recess in the body to which an element is to be anchored, inserting a non-elastic, expansible member in said recess, and a member of soft, ductile 35 metallic material disposed within said first member and forcing said ductile member outwardly thereby expanding and forcing the said first member into engagement with the wall of the recess.
7. An anchorage comprising a tubular member of relatively hard material having a spiral opening therein and a sleeve of relatively soft material filling the opening and projecting outside the bore of the tubular member. 40
8. An anchorage comprising a spiral tubular member having an opening therein and formed of relatively hard, non-elastic material and a filling of relatively soft, ductile material disposed within said tubular member and projecting through said member. 45
9. An anchorage comprising a hollow non-elastic member of relatively hard material and a filling of relatively soft, ductile material disposed within said member and adapted to force said member outwardly. 50
10. An anchorage comprising a hollow non-elastic metallic expansible member and a sleeve of relatively soft ductile metal disposed within said member and adapted to force said member outwardly. 55
11. An anchorage comprising a hollow, expansible lining of relatively hard non-elastic metal having openings therethrough, a sleeve of relatively soft ductile metal disposed therein and extending through said lining into engagement with the wall of the bore and adapted to force said lining into engagement with the wall of the bore. 60
12. An anchorage comprising a spiral tubular member of relatively hard material and a sleeve of relatively soft material, said tubular member being pressed into said sleeve. 65

In witness whereof, I have hereunto set my hand this 6th day of June, 1921.

JOHN EDWARD OGDEN.
